UNITED STATES PATENT OFFICE.

HARRY L. HERMANY, OF WANAMAKERS, PENNSYLVANIA.

FURNITURE-CASTER.

1,163,537.

Specification of Letters Patent.

Patented Dec. 7, 1915.

Application filed December 15, 1914. Serial No. 877,345.

To all whom it may concern:

Be it known that I, HARRY L. HERMANY, a citizen of the United States, residing at Wanamakers, in the county of Lehigh, State 5 of Pennsylvania, have invented certain new and useful Improvements in Furniture-Casters; and I do hereby declare the following to be a full, clear, and exact description of the invention, such as will enable 10 others skilled in the art to which it appertains to make and use the same.

This invention relates to improvements in furniture casters.

The principal object of the invention is 15 to provide a simple and novel device of this character which is anti-friction in its nature so that it will readily slide over the floor.

Another object is to provide a device of 20 this character which can be quickly and easily applied to furniture legs and effectively support the same so that said furniture can be moved with ease from place to place.

Another object is to provide a device of 25 this character which is simple and cheap in structure and which can be easily and conveniently assembled and taken apart.

Other objects and advantages will be apparent from the following description when 30 taken in connection with the accompanying drawings.

In the drawings: Figure 1 is an elevation of my improved caster shown attached to the leg of a chair, Fig. 2 is a bottom plan 35 view of the same, Fig. 3 is a transverse section on the line 3—3 of Fig. 2, and Fig. 4 is a perspective view of the inner wall cage.

Referring particularly to the accompanying drawing, 10 represents a metal plate 40 which is formed with openings 11 adjacent its four corners. Suitably secured to the under face of this plate is a downwardly tapering ring or cage 12 in the vertical wall of which are formed a circular series of 45 circular openings 13 in which are disposed the smaller balls 14. Disposed in the lower

end portion of the ring or cage is a large ball 15 which bears against the circular series of small balls 14. A ring 16 is disposed below the ball 15 and has a central opening 17 slightly smaller than the diameter of the large ball so that a portion of the ball below its central axis projects through this opening. Carried by the ring 16 are four upwardly extending arms 18 which have laterally directed apertured feet 19 which register with the openings 11 of the plate 10. Screws 20 are passed through the openings of the arms 18 and of the plate 10 and driven into the bottom of the leg 21. It will be noted that the upper portion of the cage 12 has a circular concaved seat 22 on which the balls 14 rest when said cage is in an inverted position to hold the balls while the large ball 15 is being placed therein. When 65 the large ball is so placed, the ring 16 is engaged over the ball and then the arms of the ring together with the plate 10 are secured to the bottom of the chair leg.

What is claimed is:

A caster comprising a plate, a downwardly tapering ring or cage secured to the lower side of the plate and provided with a circular series of openings and a circular concaved seat, a circular series of smaller 75 balls disposed within the openings and on the seat, a large ball disposed within the lower portion of the cage and bearing against the series of smaller balls, a ring having a central opening through which the portion of the large ball projects and arms formed integral with the ring and having perforated feet, the first-mentioned plate having openings with which the openings of the feet register to receive fastening devices. 80

In testimony whereof, I affix my signature, in the presence of two witnesses.

HARRY L. HERMANY.

Witnesses:

JAMES W. LOY,
HENRY W. KRAUSS.
